SHOE PROTECTOR

Sulo Saksa, Troy, N. H.

Application November 7, 1939, Serial No. 303,274

1 Claim. (Cl. 36—1)

This invention relates to devices in the nature of spats for covering and protecting a shoe or a part thereof, and in the preferred form extending above the shoe and protecting the wearer's ankle.

It is the general object of my invention to provide an improved construction in a shoe protector, by which the protector may be conveniently secured to a shoe and as easily removed therefrom.

A further object is to provide improved attaching means for a shoe protector, one part of which forms a permanent part of the shoe and another part of which forms an edge portion of the protector.

I also provide effective means for holding the heel portion of the protector in close association with the heel of the shoe, and for detachably securing the front and heel portions of the protector together.

My invention further relates to arrangements and combinations of parts which will be hereinafter described and more particularly pointed out in the appended claim.

A preferred form of the invention is shown in the drawing, in which

Fig. 1 is a side elevation of my improved protector applied to a shoe;

Fig. 2 is a sectional elevation, taken along the line 2—2 in Fig. 1;

Figs. 3 and 4 are partial sectional elevations, taken along the lines 3—3 and 4—4 respectively in Fig. 1; and

Fig. 5 is a partial side elevation of the protector separate from the shoe.

Referring to the drawing, I have shown a low shoe S of usual construction and having an outsole 10, insole 11, upper 12 and heel 14.

My improved shoe protector 20 in the preferred form comprises a front or toe portion 21 and a rear or heel portion 22, and is designed to cover and protect the entire upper part of the shoe S and also the ankle of the wearer.

The rear portion 22 of the protector is designed to wrap around the heel of the shoe and is preferably secured to the front portion 21 at one side of the shoe by a detachable or so-called "zipper" fastening 24. An elastic band or spring 25 is also preferably provided around the lower edge of the heel portion 22, whereby said lower edge is drawn snugly against the heel of the shoe and is maintained in close engagement therewith.

For securing the front portion 21 of my shoe protector to the front portion of the shoe, I provide a detachable or zipper fastener 30, one part of which forms the lower edge of the portion 21

of the protector 20 and the other part of which forms the outer edge of a band or strip 32 which is assembled with the shoe in the process of manufacture and which is preferably stitched between the upper 12 and the outsole 10, thus forming a permanent part of the shoe.

With this construction, my improved shoe protector may be quickly and easily applied to a shoe by passing the heel portion 22 around the heel of the shoe and closing the fastening 24, and by thereafter securing the two parts of the detachable fastening 30 along the shank and around the toe portion of the shoe.

A spring or elastic band 35 may also be provided, which extends under the shank of the shoe 15 and assists in holding the protector firmly in position.

If less complete coverage of the shoe and foot is desired, the protector may extend back only to the line X in Fig. 1, thus covering only the 20 front part of the shoe.

With my improved construction it will be seen that the front portion 21 of my protector is firmly attached around the entire shank and toe portion of the shoe, so that the protector may 25 be held firmly and smoothly over the shoe and that no gaps or openings can appear along the edges thereof. Furthermore, the heel portion 22 is closely secured to the front portion 21 and is firmly engaged with the heel of the shoe, so 30 that satisfactory contact between the protector and the shoe is effected in all parts.

Having thus described my invention and the advantages thereof, I do not wish to be limited to the details herein disclosed, otherwise than 35 as set forth in the claim, but what I claim is:

In footwear, in combination, a complete shoe having a permanent upper and having an attaching band affixed to said shoe and extending continuously from the shank of the shoe forward along one side of the shoe and around the toe portion of the shoe and rearward along the other side of the shoe to the shank, said band being secured between the permanent upper and the outsole of the shoe and forming a permanent but inconspicuous part of the shoe, and a detachable shoe protector having a cooperating attaching structure forming a continuous lower edge for said protector and coacting with said attaching band throughout its length to 45 detachably but closely and continuously secure said protector to said shoe from the shank of said shoe at one side around the toe portion of the shoe to the shank of the shoe on the other side.

SULO SAKSA. 55
